UNITED STATES PATENT OFFICE.

EDWARD N. JACOBI, OF MILWAUKEE, WISCONSIN, ASSIGNOR TO BRIGGS & STRATTON COMPANY, OF MILWAUKEE, WISCONSIN, A CORPORATION OF WISCONSIN.

SWITCH CONSTRUCTION.

Application filed April 19, 1919. Serial No. 291,249.

To all whom it may concern:

Be it known that I, EDWARD N. JACOBI, a citizen of the United States, and resident of Milwaukee, in the county of Milwaukee and State of Wisconsin, have invented new and useful Improvements in Switch Construction, of which the following is a description, reference being had to the accompanying drawings, which are a part of this specification.

This invention relates to switch construction which is particularly adapted for controlling the lighting and ignition circuits of automobiles, though it is capable of various other uses.

The invention has for its object to simplify the switch construction to make it inexpensive to manufacture, though strong and durable and of neat appearance.

Another object of the invention is to provide such a switch structure with a lock mechanism that will prevent the unauthorized operation of the switch.

With the above and other objects in view, the invention consists in the switch structure as herein claimed and all equivalents.

Referring to the accompanying drawings in which like characters of reference indicate the same parts in different views:

Fig. 1 is a front view of a switch construction embodying the present invention;

Fig. 2 is a horizontal central sectional view thereof;

Fig. 3 is a front view of a fragment of the front plate showing the switch opening thereof;

Fig. 4 is a rear view of the switch;

Fig. 5 is a similar view with the switch sectioned and the terminal head removed;

Fig. 6 is an inner face view of the terminal head with the switch case in section;

Fig. 7 is a sectional view on the line 7—7 of Fig. 5;

Fig. 8 is a detail perspective view of the key guide;

Fig. 9 is a view of the key;

Fig. 10 is a perspective view of the separate parts of one of the switch members;

Fig. 11 is a perspective view of the locking bolt therefor;

Fig. 12 is a sectional view of a modified form of the lighting switch for use with separate dim headlights;

Fig. 13 is a rear view of the terminal head for such switch construction;

Fig. 14 is a view of the key guide; and, Fig. 15 is a view of the key in the key guide.

In these drawings 15 indicates a switch panel or front plate adapted to be secured to the cowl or instrument board of an automobile by screws passed through the corner openings.

On the rear of this sheet metal switch panel is a cup-shaped sheet metal switch case 16 secured in place by means of rivets 17 passing through its closed end and through the switch panel. The rear open end of the switch case 16 has a disk-shaped terminal head 17 of insulating material 70 fitted thereto, with projecting lugs 18 on the edge of the switch case fitting in notches in the edge of the terminal head to correctly position the terminal head. While the closed end of the switch case 16 bears 75 against the back of the front plate throughout the greater portion thereof, for reasons which will later appear it is indented at certain places to form nut receiving pockets 19 in which nuts 20 may be held between 80 the end of the switch case and the back of the front plate, such pockets opening outwardly to permit of the insertion or removal of the nuts. Clamping screws 21 pass through openings in the terminal head 85 and the end of the switch case and have threaded engagement with the nuts 20 for clamping the terminal head on the switch case, the heads of said screws being preferably countersunk within the back of the 90 terminal head and provided with lock washers 22, as seen in Fig. 7.

The switch case may contain any number of switch members, but as shown there are two, alike and symmetrically arranged, and a description of one will answer for both. A circular switch opening 23 in the front plate registers with a somewhat smaller opening 24 in the end of the switch case 16 so that the two produce a shoulder, as seen 100 in Fig. 3, against which the circular base of a switch handle 25 bears, such circular base being let into the opening 23 and turning freely therein through a range of movement determined by the engagement of stop 105 shoulders 26 projecting from the bottom of the switch handle with stop shoulders formed by a projection 27 on the switch case bent inwardly from the edge of the opening 24. As seen in Fig. 10, the switch 110

- 2
- handle 25 has a shoulder 28 fitting within the opening 24 of the switch case. The projection on the bottom of the switch handle forming the stop shoulders 26 is divided 5 by a deep groove 29 in which is seated an anchor-shaped thrust plate 30 secured in place by a screw 31 passing through its shank and threading into the base of the switch handle. The larger arc-shaped end 10 of the anchor-shaped thrust plate 30 bears against the inner face of the end wall of the switch case around the opening 24, and the smaller arc-shaped end of the thrust plate 30 bears against the projection 27, as clearly 15 seen in Fig. 2, the parts being slightly bent to ensure their bearing contact without interfering with the turning movements and serving to firmly hold the switch handle against withdrawal.
- 20 The slotted projection on the base of the switch handle has an inclined face, and a sheet of insulating material 32 is clamped thereto by means of screws 33. A Y-shaped contact spring 34 is connected by rivets 35 to the sheet of insulating material 32 and a thin sheet of insulating material 36 is interposed between the sheet 32 and the face of the lug to prevent contact between the rivets 35 and screw 31 or other metal parts.
- 25 The contact spring 34 is preferably laminated or formed of more than one layer of sheet metal, and the ends of its contact arms are convexed to form rounded bearing surfaces bearing with spring pressure against 30 the inner face of the terminal head where in the different positions of the switch handle they are adapted to engage recessed contact studs 37 tightly fitting in openings of the terminal head to establish circuit connections. Screws 38 are threaded in the 35 ends of the terminal studs 37 to form binding posts and to clamp thereto metal straps forming connectors 39.
- When it is desired to lock one of the 40 switches, such as the ignition switch, for preventing unauthorized use of the automobile, a key-operated locking bolt may be provided for engaging the switch handle. A flat sheet metal strip constitutes the locking 45 bolt 40 slidably mounted in a groove 41 formed by a slot cut through the closed end of the switch case 16 and extending from one switch member to the other. The locking bolt is confined in the groove 41 formed 50 by this slot and the back of the front plate by the large arc-shaped ends of the thrust plates 30. A projection 42 on one side of the lock bolt 41 travels in an off-set portion of the slot 40 and is bent up at an angle 55 to the plane of the locking bolt and is slotted to receive the end of a spring 43 which is riveted to the side wall of the switch case at 44 by rivets cut from the wall of the switch case. The tendency of the spring is 60 to force the locking bolt 40 to the right, as seen in Fig. 5, so that its reduced end will engage with a locking notch 45 formed in the shoulder 28 of the ignition switch handle, shown in Fig. 11. The other end of the locking bolt is incapable of engaging the 65 lighting switch handle as it is shorter.
- A key 46, such as shown in Fig. 9, is adapted to be entered through an opening in the front plate for moving the spring 43 and thereby sliding the bolt out of its engagement with the ignition switch handle. A bent-up sheet metal key guide, shown in Fig. 8, forms a slotted cup-shaped escutcheon plate 47 rotatably mounted in a circular opening in the front plate. At diametrically opposite points the rearwardly turned edges of the escutcheon plate are provided with outwardly projecting lugs 48 to bear against the back of the front plate. An arc-shaped recess 49 is formed in the edge of the opening in the end of the switch case to accommodate one of the lugs 48 and form stop shoulders engaged thereby for limiting the turning movements of the escutcheon plate, while an arc-shaped depression is formed in the opposite portion of the opening in the end of the switch case to produce between it and the front plate a pocket 50 to accommodate the other lug 48. The lug 48 confined in the pocket 50 serves to steady the escutcheon plate and take the inward end-thrust thereof.
- The key guide further comprises a flaring side channel 51 formed by a continuation of the metal of the edge of the escutcheon plate next to the lug 48 which travels in recess 49.
- The side channel 51 formed by opposite flanges and a connecting web is flaring at its upper end, as seen in Fig. 14, to facilitate the entry of the key, and the flanges are parallel near their lower ends. At its lower end the key guide has an end-piece 52 formed in extension of the web portion of the side channel 51 and bent over to lie against the opposite flanges of the channel portion, and said end-piece is provided with an opening 53 centered on the axis of the key guide and fitting around a post 54 projecting from the inner face of the terminal head 17. The post 54 is embedded in the terminal head 17 and projects beyond the end-piece 52 of the key guide, the parallel flanges of the key guide being cut away at 55 to accommodate it. The post 54 stands up from the terminal head to have its end lie about even with the front edge of the spring 43, which passes close to it and beside serving as a pivotal mounting for the key guide it blocks the entry of a blade, such as a screwdriver, and prevents it from gaining access to the spring for false operation of the lock. The key 46 is flat and just fits within the slot in the escutcheon plate and within the side channel 51 of the key guide,

and is provided with a slot 56 in its end to receive the end of the post 54, and when it is turned the key guide turns with it and its side which is not contained in the channel bears against the spring 43 to produce the movement of the locking bolt.

A lug 57 projects rearwardly from the edge of the pocket 50 in position to be engaged by a shoulder 58 on the side of the key when the key is in the position in which it is entered in the lock, such lug assisting in guiding the key to its proper position. At the edge of the opening in the end of the switch case there is a lug 59 projecting inwardly to engage in a notch 60 in the edge of the key when the key is in the position in which the switch is unlocked, thus serving to prevent the withdrawal of the key and preventing the operation of the switch by means of a key not provided with such notch.

The switch illustrated may be used for controlling the lights and the ignition, and the ignition switch may be locked by the removal of the key, either when the switch is in its "off" position, or in one of its "on" positions. When the key is removed when the switch is in one of its "on" positions, the switch is not locked until it is returned to its "off" position, at which time the spring 43 returns the locking bolt 40 to the notch 45 of the ignition switch handle and thus prevents further movement of the ignition switch. Any desirable wiring connections may be made with the contact studs 38 on the back of the terminal head, and when one set of headlight lamps are used a resistor 61 may be connected between the two extreme contact studs of the lighting switch, but when said studs are connected separately to large and small headlights, as indicated in Fig. 13, it may be desirable to provide a supplemental contact stud 62 containing a spring-pressed plunger 63 bearing against the forked contact spring 34 so as to make connection for the rear lights whenever the switch is in position for making either of the headlight connections.

What I claim as new and desire to secure by Letters Patent is:

1. In a switch, a front plate, a switch case having one end open and the other end secured to the back of the front plate and provided with indentations forming pockets with the back of the front plate, nuts fitting in said pockets, a terminal head fitting on the open end of the switch case, and screws passing through the terminal head and threaded in the nuts.

2. In a switch, the combination of a front plate, a cup-shaped switch case with its closed end secured to the back of the front plate and provided with indentations forming pockets with the back of the front plate, nuts fitting in the pockets, lugs projecting

from the rear open end of the switch case, a terminal head bearing against the rear end of the switch case and having notches in which the lugs fit, and screws passed through the terminal head and the indentations of the switch case and threaded in the nuts.

3. In a switch, the combination of a front plate, a cup-shaped switch case with its closed end secured to the back of the front plate, there being registering openings in said end of the switch case and the front plate, the opening in the end of the switch case being smaller than the opening in the front plate, a switch handle having a thrust shoulder fitting within the opening of the front plate and against the exposed edge of the end of the switch case, a thrust plate secured to the switch handle and bearing against the inner surface of the end of the switch case, a switch member mounted on the switch handle, and a terminal head secured to the open end of the switch case and provided with contacts engaged by the switch member.

4. In a switch, the combination of a front plate, a cup-shaped switch case with its closed end secured to the back of the front plate, there being an opening in the front plate registering with a smaller opening in the end of the switch case, a switch handle fitting in the opening of the front plate and bearing against the exposed edge of the opening in the switch case, there being a slot in the end of the switch handle, a thrust plate passing through said slot and bearing on the end of the switch case, a strip of insulating material secured to the end of the switch handle across the slot, a switch member secured to the strip of insulating material by securing means disposed within the slot, and a terminal head on the end of the switch case having contacts engaged by the switch member.

5. In a switch, the combination of a front plate, a cup-shaped switch case secured to the back of the front plate, there being registering openings in the front plate and the end of the switch case, a switch handle passing through said openings and provided with an inclined slotted end, a thrust plate secured to the switch handle within the slot, a strip of insulating material secured to the end of the switch handle across the slot, an inclined contact spring having securing means connecting it with the strip of insulation and disposed within the slot, a sheet of insulating material between the insulating strip and the end of the switch handle covering the connecting means, and a terminal head at the end of the switch case having a contact engaged by the contact spring.

6. In a switch, the combination of a front plate, a cup-shaped switch case secured to the back thereof, there being an opening in

the front plate registering with a smaller opening in the end of the switch case, stop shoulders in the switch case opening, a switch handle passing through the registering openings and provided with shoulders for engaging the stop shoulders, a thrust plate secured to the switch handle and bearing against the inner face of the switch case, a switch member carried by the switch handle, and a terminal head on the end of the switch case having a contact engaged by the switch member.

7. In a switch, the combination of a front plate, a cup-shaped switch case secured to the back thereof, there being registering openings in the front plate and the end of the switch case, a switch handle passing through the registering openings, a thrust plate secured to the switch handle and bearing on the inner face of the switch case, a switch member mounted on the switch handle, a terminal head in the end of the switch case having a contact engaged by the switch member, there being a slot in the end of the switch case, a lock bolt slidably mounted in the slot and confined by the thrust plate, and means for operating the bolt, there being a recess in the switch handle engaged by the locking bolt in one position thereof.

8. In a switch, the combination of a front plate, a cup-shaped switch case secured to the back of the front plate, there being registering openings in the front plate and the switch case, a switch handle passing through said openings, a thrust plate secured to the switch handle and bearing on the inner face of the end of the switch case, a switch member carried by the switch handle, a terminal head having a contact engaged by the switch member, there being a slot in the end of the switch case, and a key-operated spring-pressed locking bolt slidably mounted in the slot and confined by the thrust plate, there being a recess in the switch handle to receive the end of the locking bolt.

9. In a switch, the combination of a front plate, a cup-shaped switch case secured to the back thereof, there being registering openings in the front plate and the end of the switch case, a switch handle passing through the registering openings and provided with a slotted end, an anchor-shaped thrust plate fitting in the slot and secured to the switch handle and bearing on the inner face of the switch case, a switch member carried by the slotted end of the switch handle, a terminal head having a contact engaged by the switch member, a slot in the end of the switch case, and a spring-pressed key-operated lock bolt slidably fitting in the slot and confined by the arc-shaped end of the anchor-shaped thrust plate in the different positions of the switch handle, there being a recess in the switch handle engaged by the locking bolt in one position thereof.

10. In a switch, the combination of a front plate, a switch case secured thereto, a switch handle passing through openings in the front plate and the switch case, a switch member on the switch handle, a terminal head on the switch case having a contact engaged by the switch member, a slidably mounted lock bolt adapted to engage a recess in the switch handle, a spring secured to the switch case and engaging the lock bolt, a post standing up from the terminal head, a key guide comprising a channel member having an escutcheon plate at one end fitting in an opening in the front plate and an opening at the other end fitting on said post, and a key adapted to be entered through a slot in the escutcheon plate and having a slot on its end to permit it to straddle the post, said key when turned with the key guide serving to engage and move the spring. 85

11. In a switch, the combination of a front plate, a cup-shaped switch case secured to the back thereof, a terminal head on the switch case, a switch member within the switch case operated by a handle passing through the front plate, a flaring channel shaped key guide having an escutcheon plate at one end fitting in an opening in the front plate and a projection at the other end provided with an opening, a post on the terminal head fitting in the opening of said projection, oppositely extending lugs on the escutcheon plate, there being a recess in the end wall of the switch case to receive one of the lugs forming stop shoulders at its ends for limiting the movement of the key guide, a pocket formed by a depression of the end of the switch case away from the front plate to contain the other lug, a projection on the pocket, a key adapted to pass through a slot in the escutcheon plate and provided with a slot on its end to permit it to straddle the post and having a projection to bear against the projection on the pocket, a lug on the end of the switch case adapted to enter a notch in the edge of the key when the key is in unlocking position for preventing the removal of the key, a spring secured to the switch case and engaged by the key when it is moved to its unlocking position, and a locking bolt 115 engaging the spring and adapted to be held thereby in locking engagement with the switch handle.

12. In a switch, the combination of a front plate, a cup-shaped switch case secured to the back thereof, a pair of switch handles passing through openings in the front plate and the end of the switch case, thrust plates secured to the switch handles and bearing on the inner face of the end of the switch case, 125 contact springs mounted on the switch handles, a terminal head on the switch case having contacts engaged by the contact springs, there being a slot in the end of the switch case, a locking bolt slidably mounted in the 130

slot and confined therein by the thrust plates of both switch handles, a spring secured to the switch case and engaging the lock bolt, a recess on one switch handle entered by the lock bolt, and means for removing the lock bolt from the said recess.

13. In a switch, the combination of a front plate, a switch case secured thereto, a switch handle having an inclined end, a contact spring mounted on the inclined end of the handle, a terminal head in the end of the

switch case having a contact engaged by the contact spring, a terminal stud in the terminal head opposite the switch handle, and a spring-pressed plunger in the terminal stud 15 bearing on the contact spring.

In testimony whereof, I affix my signature, in presence of two witnesses.

EDWARD N. JACOBI.

Witnesses:
